J. H. R. WARD,
ELECTRIC ARC LAMP.

No. 449,236.

Patented Mar. 31, 1891.

UNITED STATES PATENT OFFICE.

JOHN H. R. WARD, OF NEW YORK, N. Y., ASSIGNOR TO THE UNIVERSAL
ARC LAMP COMPANY, OF SAME PLACE.

ELECTRIC-ARC LAMP.

SPECIFICATION forming part of Letters Patent No. 449,236, dated March 31, 1891.

Application filed December 8, 1890. Serial No. 373,942. (No model.)

To all whom it may concern:

Be it known that I, JOHN H. R. WARD, a citizen of the United States, and a resident of New York, county and State of New York, 5 have invented certain new and useful Improvements in Electric-Arc-Lamp Shade-Holder, (Case 3,) of which the following is a specification.

My invention relates to the mechanical construction of that portion of an electric-arc lamp for supporting the usual transparent or translucent shade or globe.

The object of the invention is to provide means whereby the removal of the globe may be facilitated during the adjustment of the 15 carbon-rods of the lamp and whereby the globe may be again adjusted to its proper position.

The details of the device embodying the 20 invention are set forth in the accompanying drawings.

Figures 1 and 2 are vertical elevations at right angles to each other of a lamp equipped with my invention. In Fig. 2 a portion of 25 the globe is broken out on the near side. Fig. 3 is a view of the device in the same direction as seen in Fig. 1. The dotted lines in Fig. 3 are in a position of certain sections shown in subsequent figures. Fig. 4 shows a 30 section at the line Y, looking downward, all portions below the line Y being omitted. Fig. 5 is a sectional view at the line Z, looking downward as far as the line W. Fig. 6 is a sectional view at the line S, looking downward. 35 Fig. 7 is a view of one of the hooks and handles or rings, partly in section as to those parts supporting the hook. Fig. 8 is the lower part of the frame of the lamp in plan view.

The device embodying the invention consists of the combination of a lamp a, provided 40 with vertical tubes b, suspended therefrom and forming a part of the frame of the lamp; a cross-piece c, also forming a part of the frame and connecting rigidly the lower ends 45 of the tubes b and provided with beveled holes d in opposite ends thereof, the smaller ends of the holes being at the lower portion of the cross-piece c; a clasp e, having projections f and attached at equal heights on the 50 respective tubes b, the projections f being separated from each other, except as to a pin

g, connecting the same in each clasp, the pin being horizontal and retaining the projections in such a manner as to hold the clasp rigidly on its tube; a globe-socket h, carrying the 55 globe i and carried by a cross-piece c', which connects two vertical rods b', which pass upward through the beveled holes d and terminates in handles or thumb-b-rings j and sliding rings j', each sliding ring being at right angles to the thumb-ring, the rings j' surrounding the tubes b, the rings j' being oval in such a direction that they may be pulled away from each other; hooks m, attached to the rings j on those sides facing the tubes b and normally supported on the pins g, and a cup n 60 for catching oil, particles of unburned carbon, &c.

A indicates one of the conductors passing to the lower carbon-holder B. Through one of the tubes C are set-screws for retaining the globe i within the socket. The cross-piece c is provided with a central hole D, in which is attached the carbon-holder B in an insulated manner by the insulating-spool E. On each 75 side of the hole D are located holes F, through which pass the ends of the tubes b, which are secured to the cross-piece by shoulders G and nuts B'.

The pins g represent, typically, any suitable projection to the tubes b for supporting the hooks m, whereby the weight of the globe, its socket, and holder are prevented from falling from their highest position (shown in Figs. 1 and 2) to a lower position. (Shown also 85 in Fig. 4.)

The operation of the device is described as follows: Supposing that the globe is in its highest position, which is a normal position, and that the hooks m rest upon the pins g, 90 the operator grasps one of the rings j in each hand and pulls them in opposite directions, whereby the said hooks are released from said pins, and then he allows the globe holder or socket h, together with those parts attached 95 to it, to fall until the sliding rings j' rest upon the shoulders G. The rods b', being of considerable length in proportion to their diameter, are elastic and flexible, being made preferably of hard brass. When pulled apart and 100 then released, they spring back to their original position. When the carbons have been

adjusted and any other desirable matters attended to, the operator raises the globe by grasping each ring *j* and raising the same. He then pulls the rings apart so that the hooks *m* are brought above the pins *g*, where they are allowed to rest.

I claim as my invention--

An electric-arc-lamp globe-holder consisting of the combination of a globe-socket, *10* elastic and flexible rods carried thereon, two rings at the opposite end of each rod at right angles to each other, tubes suspended from the lamp parallel to each other and said rods and passing through one of the rings on each

rod, hooks attached to the remaining rings, *15* supports, such as pins *g*, attached to said tubes for the purpose, as described, of supporting said hooks, and a cross-piece connecting the lower ends of said tubes and provided with holes through which pass said rods. *20*

In testimony that I claim the foregoing as my invention I have signed my name, in presence of two witnesses, this 1st day of May, 1890.

JOHN H. R. WARD.
